DOOR CASING

Wilbur L. Lang, Omaha, Nebr.

Application September 15, 1948, Serial No. 49,342

1 Claim. (Cl. 189—46)

1

This invention relates to building construction and more particularly it is an object of the invention to provide a door casing of a construction adapted to be made from extruded materials.

It is well known that wooden door casings of the conventional type are formed of a plurality of separate pieces each requiring separate milling and individual installation. During recent years the cost of mill work and labor have advanced so greatly that it is desirable to conserve construction steps by new methods.

It is therefore an object of this invention to provide a door casing which may be constructed by extrusion from plastic and other materials.

Another object of the invention is to provide a door casing construction which is adapted to be manufactured from a minimum volume of stock.

Yet a further object of the invention is to provide a door casing as described which is of a construction adapted for the use of plastic materials of colors and designs such that no painting of the installed door stop is necessary.

A particular object of the invention is to provide a door casing which may be quickly installed.

A further object resides in the provision of a construction which may be formed of a plurality of extruded sections or in a single integral piece as desired.

Another object of the invention is to provide a device for the purpose described which is sturdy and durable in construction, reliable and efficient in operation, and relatively simple and inexpensive to manufacture, assemble and utilize.

Other and still further objects and advantages of the invention will become apparent from the following detailed description of a preferred embodiment thereof:

In the drawings:

Figure 1 is a horizontal cross-sectional view of a vertical side of the doorway opening and a broken away portion of the adjacent wall, showing the casing of this invention installed thereon, an attached door being only partially shown the remainder of the door being broken away;

Figure 2 is a side elevation of the parts shown in Figure 1 as seen from the right hand side thereof, a portion of the doorway and a portion of a hinge employed being broken away and other portions showing in section; and

Figure 3 is an end elevation of the parts shown in Figure 1 as seen from the bottom thereof.

Referring now to the drawings for a more particular description, 10 and 12 indicate two two-by-four studdings disposed with their widest sides abutted for forming the vertical side of the doorway opening.

2

This invention provides a casing assembly for attachment to the vertical side of the doorway opening. Such casing includes an elongated corner member 20 having two preferably integral longitudinal sections 22 and 24.

The sections 22 and 24 are disposed at right angles to each other for extending about that one of the corners of the studding 12 which is disposed adjacent the doorway opening.

10 The section or inner side plate 22 is tapered from a greater thickness at the intersection thereof with the section or end plate 24 to a lesser thickness at the terminal end of the section 22.

15 The section 22 is tapered in the form of a wedge, the inner side of the section 22 being disposed at a right angle with respect to the section 24 and the outer side of the member 22 being inclinedly disposed with respect to the inner side thereof.

20 The purpose of the wedge or tapered section 22 is for insertion between a plaster base material 40 and the adjacent studdings 10 and 12.

An elongated moulding member 30 is provided which includes a longitudinal section or flange 32 disposed in use transversely to the tapered section 22. The section 32 is preferably spaced apart from the tapered section 22 sufficiently for the reception therebetween of a plaster base material 40 which may be of any conventional construction.

25 The transverse section 32 is provided with two approximately parallel vertical, longitudinal edges 44 and 46.

30 The moulding member 30 is also provided with a longitudinal face section 50 which latter is vertically disposed having one of its vertical sides connected to the transverse section 32 at the outer longitudinal edge 46 of the transverse section 32.

35 As thus described, the transverse section 32 forms a guide or base to level a subsequent coat of plaster 54 against. The face section 50 is preferably provided with a concave arcuate longitudinal portion for purpose of appearance. Other ornamental shapes may be used if desired.

The other longitudinal side or flange 58 of the face portion 50 is secured to the tapered section 22 adjacent but spaced apart from the section 24.

40 As thus described, the face portion 50 is provided with a flat surface or outer side plate section 60 adjacent the transverse section 32, which may be used as a plastering guide. It is preferable that portions of the face section 50 which are disposed between the flat surface 60 and the edge 58 be disposed closer to the tapered sec-

tion 22 than is the flat portion 60 so as not to interfere with the movements of plasterer's tools.

A similar elongated corner member 20' and a similar moulding member 30' are employed for extending around the other corner of the two-by-four 12 at the doorway opening.

All parts of the members 20' and 30' are similar and bear similar, but prime numerals. Similar plaster boards 40' and plaster 54' are also disposed on the opposite sides of the two-by-four studdings 10 and 12.

The section 24' is preferably longer than the section 24 and extends a greater distance across that face 70 of the two-by-four 12 which faces the doorway opening.

It is sometimes desirable that the two elongated corner members 20 and 20' be attached separately to the two-by-four 12. In such cases, it is desirable that the sides 24 and 24' together stretch less than completely across the surface 70. This is particularly useful in instances where the studdings 12 are of varying width in cross-section.

The casing assembly further includes an elongated door stop member 80. The door stop member 80 is provided with a longitudinal section or flange 82 which is disposed in use transversely to the sections 24 and 24' of the corner member.

The transverse section 82 of the stop member 80 is for disposal opposite the side of and adjacent a door 90 in use, as best shown in Figure 1. The longitudinal edges of the section 82 of the stop member 80 are disposed in substantial parallelism and the stop member 80 is further provided with a face portion or section 96, which is connected to the outer longitudinal edge of the door opposing portion 82.

The face portion 96 is provided with another longitudinal edge or flange 98 which is disposed in vertical parallelism with that edge of the longitudinal stop section 82 which is disposed in use adjacent the corner member section 24'.

The face portion 96 of the stop member 80 may be provided with concave or convex arcuate surfaces as desired for providing the stop member with an artistic design.

The door 90 is mounted upon hinges 100 having leaves 102 and 104 which latter are respectively secured by means of screws 106 to the door 90 and the two-by-four 12.

It is desirable that a notch 110 be provided in the corner member section 24' for receiving the leaf 104 of the hinge 100.

It will be seen that all members and sections described may be extruded integrally in one piece for economical manufacture. Also all members are hollow and may be formed of material as thin as is consistent with the strength required.

It will be seen also that each corner member and its moulding member may be integral to form two separate units, the stop member being employed as a separate unit to be secured on the job to the corner members 20 and 20' to cover the gap between the ends of the sections 24 and 24'. Also, if desired, the moulding members 30 and 30' may themselves be separate pieces.

This invention has provided an economical 70 casing assembly for attachment to a doorway opening which will save manufacturing steps and installation steps now conventionally used, which will facilitate the manufacture of a product which will not require painting and which 75

can greatly increase the speed of building construction.

From the foregoing description, it is thought to be obvious that a door casing constructed in accordance with my invention is particularly adapted for use by reason of the convenience and facility with which it may be assembled and operated, and it will also be obvious that my invention is susceptible of some change and modification including variations in the shape and size of the parts without departing from the principles and spirit thereof, and for this reason I do not wish to be understood as limiting myself to the precise arrangement and formation of the several parts herein shown in carrying out my invention in practice, except as claimed.

I claim:

A sheet metal door frame comprising a pair of L-shape corner sections adapted to be positioned over the opposite corners of studding with end plates positioned to lie against the wide side face of the studding and inner side plates having tapering side surfaces extended at right angles from the edges of the end plates and adapted to be positioned against the ends of the studding whereby the studding nests in the said corner sections, the said side plates tapering from the points of intersection thereof with the said end plates to provide thin extended edges for insertion under base material of walls carried by the studding, said side plates having outwardly extended flanges positioned perpendicular to the surfaces of the side plates and spaced from the intersections of the side plates with the end plates, arcuate outwardly disposed webs extended from the outer edges of the flanges to points spaced inwardly from the end plates, outer side plate sections extended from the edges of the arcuate webs inwardly from the end plates and positioned parallel to the said inner side plates, said outer side plate sections having inwardly extended flanges on the edges thereof and said flanges spaced from and positioned in planes perpendicular to the said inner side plates, the thin extended edges of the said inner side plates extended beyond the flanges of the outer side plate sections providing supporting means for the wall surface carried by the studding and the said flanges of the outer side plate sections providing stops for the outer finishing plaster layer of the wall, the outer surface of which being flush with the outer surface of the said outer side plate sections, and stops, substantially channel-shape in cross section, covering the extended edges of the end plates of the said corner sections of the frame.
